Primary Examiner — Michelle E. Wilson*Assistant Examiner* — Richard E Yenchesky(74) *Attorney, Agent, or Firm* — Carter, DeLuca & Farrell LLP; George Likourezos(57) **CLAIM**

The ornamental design for a liquid-submersible vacuum cleaner, as shown and described.

DESCRIPTION

FIG. 1 is a perspective view of a liquid-submersible vacuum cleaner in accordance with the present design;

FIG. 2 is a front view thereof;

FIG. 3 is a rear view thereof;

FIG. 4 is a top view thereof;

FIG. 5 is a bottom view thereof;

FIG. 6 is a right view thereof; and,

FIG. 7 is a left view thereof.

The broken lines shown in the drawings illustrate portions of the liquid-submersible vacuum cleaner that form no part of the claimed design.
